UNITED STATES PATENT OFFICE

2,633,171

METHOD OF HULLING, WASHING, AND DRYING OF GRAIN, WITH SIMULTANEOUS SCREENING

Arthur C. Daman, Denver, Colo., assignor to Mining Process and Patent Company, Denver, Colo., a corporation of Colorado

Application August 23, 1947, Serial No. 770,211

18 Claims. (Cl. 146—221.6)

1

This invention relates to methods for the dry treatment of grain such as wheat, whereby to prepare the grain for milling or other conversion into food stuffs.

The invention is particularly applicable to the hulling of wheat for the removal of the outer integument or bran layer without rupture of the kernels themselves.

A particular object of the invention is to provide a method for the removal of bran from wheat kernels, or the removal of corresponding outer coverings from similar grains, by a dry process particularly adapted for operation without the employment of water except as a subsequent washing step.

Another important object of the invention is to provide for the hulling of wheat and the like by only a vibrating action to effect the actual loosening of the outer bran layer from the various kernels.

A still further object of the invention is to provide a method by means of which wheat may be continuously hulled, the loosened bran separated from the hulled kernels, such kernels being also freed from small, heavy, foreign materials, washed free of adhering foreign materials, and quickly dried in preparation for milling, packaging, or other desired disposition.

Another object of the invention is to provide a process by means of which contact objects, such as balls, associated with the grain being treated are relied upon in conjunction with the mentioned vibrating action to effect cracking or splitting and loosening of the grain hulls from the kernels without rupture of the kernels themselves.

A further object of the invention is to provide a hulling process employing pressure in conjunction with a plurality of contact objects to accomplish cracking or splitting of the hulls, and loosening of the hulls from the kernels during vibration, it being a more specific object to rely upon the weight of the column of the grain to furnish the required pressure which effects the necessary hull splitting under the influence of the vibration imparted to the column of grain and contact objects.

A more particular object, which is of overall importance in connection with a treatment of this type, is to start with dry grain as normally supplied for grain treating purposes, remove the hulls from the dry grain, separate foreign materials from the hulled grain, and furnish the product in thoroughly dry form for future handling.

Other objects and various features of the invention will become apparent to those skilled in

2

the art upon reference to the following specification and the accompanying drawing wherein one embodiment of the invention is disclosed for the purpose of exemplification.

5 In the drawing:

Fig. 1 is a perspective view illustrating somewhat diagrammatically an apparatus constructed in accordance with the invention and representing the novel process;

10 Fig. 2 is a cross section indicating a rubber ball as one of the contact objects;

Fig. 3 is a cross section indicating a rubber ball with a metallic core as one of the contact objects;

15 Fig. 4 is an elevational detail showing suspension means for a table mounting carrying the vibratory mechanism;

Fig. 5 is a longitudinal sectional detail indicating the drive means by which the required vibration is effected; and

20 Fig. 6 indicates a modified means for providing the grain column.

The form of the invention illustrated comprises a generally horizontally disposed flat support, such as a screen 10 of suitable mesh, which constitutes a surface upon which rests a column 12 of grain to be hulled, such as wheat, which column is established by and contained within a vertically disposed cylinder 14. The cylinder 14 may be sectional and telescopic as illustrated, both sections shown being vertically adjustable by separate means, such as rack and pinion devices 14a illustrated. The cylinder 14 is open at its lower end in order to expose the column of grain to the screen 10 or other flat support used, and it is also open at its upper end to receive grain from a feed chute 15 adapted to be supplied from any appropriate source, such as a storage bin.

An important agent in the operation of the process is a plurality of contact bodies, illustrated as rubber balls 16, which are disposed in the lower end of the grain column 12. These balls, which may be of solid, heavy rubber as indicated in Fig. 2, or kindred resilient material, or may contain a metal core 16a as indicated in Fig. 3, maintain themselves in the lower portion 45 of the grain column 12 or at any appropriate operative level during the hulling operation. They are employed in such numbers as required to effect the desired result, and may constitute, for example, two or more layers of balls, approximately as illustrated.

The upper end of the flat support, under the cylinder 14, may be either an extension of the screen 10 or a perforate or imperforate plate 17 upon which the grain and balls 16 rest. Sometimes it is not essential to have the grain abso-

lutely dry, and in such cases a light water spray may be applied at the top of the grain column 12 as by a spray head 18, or a heavy water wash if required.

The vibratory action of the screen 10, as presently to be more fully described, results in the movement of the kernels of grain and the hulls, such as bran, which have been removed therefrom, out from under the lower edge of the cylinder 14. This movement may be effected solely through the vibrating action produced, or may be facilitated by a slight inclination in the screen 10 in the direction of desired travel. The screen 10 may be of such mesh that small solids, including small, broken pieces of grain, may pass therethrough. The whole grain layer and the hulls then travel under an elongated suction hood 20 disposed transversely of the screen 10, suction being accomplished through an upstanding suction pipe 22 leading to a suction fan or any other type of suction device. Bran and other light constituents are removed from the grain layer on the screen 10 as the grain passes under the hood 20. The grain, freed from hulls and other non-adherent foreign material, continues to travel along the screen and then passes under a spray of water which is supplied by a water line 23 and issues from any type of elongated spray head 24, such as the perforated pipes shown. Leaving the spray head 24, the washed grain, now free from powdery and flaky materials and water soluble materials, is passed under a drying device, which is shown as a hot air blower hood 25 supplied with hot air through a feed pipe 26 leading from any mechanism adapted to supply suitably heated air under appropriate pressure. The heated air passes over and around the wet or damp grain moving along the screen 10, thereby drying the grain, the moisture and air passing through the screen and being disposed of as desired. A perforated spreader plate 27 located in an intermediate portion of the hood 25 properly distributes the heated air passing to the moist grain.

In the form of structure illustrated, the solid and liquid material will fall onto a table 30 and discharge from the nearest end seen in Fig. 1, and escaping air may issue from the same end of the table 30 and through the meshes of the screen 10 in the vicinity of the blower hood 25.

The screen 10 is carried upon the table 30 through the medium of side walls 31 upstanding from the table 30.

With respect to the construction of the table 30, mounting of the screen 10 therein, and the mounting of the parts for the required vibratory movement, such is accomplished by appropriately securing and positioning the screen 10 upon the table 30 so that vibration of the table 30 will be desirably imparted to the screen 10. For this purpose, an elongated angle plate 32 is provided along each of the side walls 31, the respective plate 32 being secured in position by standard carriage bolts 33, or the like. To stretch this screen 10, the lower edge of each angle plate 32 is provided with a flange which engages in folded reinforcing means 34 secured to the respective edge of the screen, this folded means 34 resting upon a corresponding elongated bracket plate 35 secured to the adjacent side wall 31, as by welding or otherwise. Thus, when the two angle plates 32 are drawn into position, the edges of the screen 10 are tensioned and bound against the bracket plates 35. For the purpose of maintaining desirable operative positioning of the median portions of the screen 75

10, elongated rubber cushions 36, carried upon the upper edges of elongated angle bars 38, may be used, the bars 38 being positioned with respect to the table 30 as desired. Should camber be required in the median portion of the screen 10 whereby to insure proper disposition of the moving, hulled grain, the upper faces of the rubber cushions 36 will be correspondingly elevated.

10 The table 30 is mounted for vibration by having its side walls 31 appropriately secured to main side plates 40, as by bolts 41. As illustrated, the upper edges of the main side plates 40 are conveniently provided with outwardly directed flanges 42, and the lowermost corners at the opposite ends of the apparatus are properly spaced by means of tie rods 43 appropriately attached thereto.

20 For the purpose of mounting the main side plates 40 to accommodate the vibratory motion required to be imparted thereto and hence to the table 30 and the screen 10, the outer face of each end portion of each main plate 40 has secured thereto an open-front rectangular box bracket 45 having a back wall 46 welded or bolted to the respective main side plate 40. Each bracket 45 projects loosely into a rectangular frame 47 which is open at the back, and may be open at the front. The lower end of the frame 30 47 is provided with ears 48 by means of which it is bolted to an appropriate base member 49.

30 35 The top bar 47a of each frame 47 carries a suspension rod 50 which is suspended therefrom by means of lock nuts 52 secured on its upper threaded end. The rod 50, in each instance, depends within the respective frame 47, passing through both the upper and the lower ends of the respective box bracket 45. Within each box bracket 45 and disposed around the suspension rod 50 is a supporting spring 54 upon which rests the upper wall of the box bracket 45, whereby the corresponding corner of the vibratory structure is supported. This weight is transmitted through the spring 54 to the suspension rod 50 and thence to the respective frame 47 by way of a rubber cushion 55 (Fig. 4) disposed in a retainer cup 56 resting upon a mounting 58 fixed upon the lower end of the rod 50 and reciprocably positioned within a corresponding opening in the lower end wall of the respective box bracket 45.

40 45 Thus, the vibratory structure consisting of the main side plates 40, the table 30, and its upstanding side walls 31, together with the screen 10, is carried upon four springs 54 supported from four frames 47 which in turn rest upon four appropriate base members 49. By this mounting means, vibratory motion is readily permitted, a suitable pendulum effect being provided which results in avoidance of the transmission of destructive vibration and provides only for that vibration of small amplitude which is required for the present purpose.

50 55 60 To effect the required vibration, a motor 60 carried upon any suitable support 61 is employed to drive a V-belt 72 passing over a driven pulley 63 mounted alongside a fly wheel 64 upon one end of a vibration producing shaft 65. The shaft 65 is mounted at each end in bearings 66, Fig. 5, carried in the side walls 31 of the table 30 and in the main side plates 40 to which the side walls 31 are bolted as above described. The middle section of the shaft 65 is provided with an eccentrically disposed elongated portion 67 having but slight eccentricity and capable of producing high speed vibration of very small amplitude

which is the character of vibration necessary to accomplish the results of this invention. For the purpose of attaining the necessary vibratory action, the fly wheel 64 may be provided with a replaceable or adjustably disposed weight 68, which may be employed either to assist or offset the effects of the eccentric portion 67. To accomplish desired balance, a second fly wheel 64 is disposed on the end of the shaft 65 hidden from view in Fig. 1.

Operation

The vibratory mechanism, comprised of the screen 10, the table 30, and the main side plates 40, is vibrated through the medium of the motor 60 and the drive shaft 65, as above indicated, to yield vibration of very small amplitude and high rate, proper transmission of this vibration being permitted by the mounting of the box brackets 45 upon the spring 54 carried on the suspension rods 50 and supported upon the frames 47 disposed at the corners of the apparatus.

A number of the contact objects, such as the rubber balls 16 illustrated, are disposed upon the screen 10 or the plate 17, as the case may be, and in the lower portion of the cylinder 14 to produce as many layers as required to effect the desired result, and grain, such as wheat, is fed continuously through the chute 15 to maintain the grain column 12 as a head of proper value to provide the pressure upon the balls 16 necessary to effect splitting or other appropriate rupture of the grain hulls, without, however, rupturing or crushing the kernels themselves. The balls 16 may be of different sizes best calculated to produce the necessary function. For example, balls one-half inch in diameter, or two inches in diameter, or even larger diameter, perhaps up to six inches may be employed, the larger sizes being used especially in conjunction with the employment of balls of varying sizes, such as those of one-half inch and one inch diameters. Spacing of the cylinder 14 from the screen 10 is such that, as the screen 10 is vibrated, the lowermost grain is caused to pass under the lower edge of the cylinder 14 together with the bran or other hulls which have been detached by the vibratory action. Such spacing may be regulated by adjustment of the lower section of the cylinder 14 by its rack and pinion device 14a. Adjustment of the upper cylinder section through its rack and pinion device 14a may be employed in establishing the proper height of the grain column 12 for any given grain being hulled. If desirable, the grain column 12 may be formed by a rectangular hopper 70, Fig. 6, transversely disposed across the screen 10 and affording a mouth of uniform dimensions both laterally and longitudinally of the screen 10.

Continued vibration causes the grain and hulls to advance toward the suction hood 20. During this interval, small, solid particles, such as grit and small broken pieces of grain, pass through the screen 10, the mesh of which, however, is small enough to retain full size grain. As the hulled grain and hulls pass under the suction hood 20, the hulls are drawn upward through the pipe 22 by the passage of air which enters from the underside of the screen 10, thus removing from the hulled grain all light weight materials.

Continued motion of the grain, from which the hulls and other light materials have been removed, brings the grain under the spray head 24 where the hulled grain is washed to remove

adhering powdery materials and water soluble substances. The water falls through the meshes of the screen 10 onto the table 30 and the continued vibration after the grain leaves the spray 5 causes water droplets to be shaken off. The remaining thin water film is removed by the warm or hot air blast as the grain passes under the hood 25. The hulled, dried grain is then delivered from the screen 10 to any receiver 10 which may be a chute, a conveyor belt, or other structure as preferred. While the structure disclosed 15 signifies that wash water and other materials passing through the screen 10 are delivered from the nearest end of the table 30, it is obvious that other dispositions may be made as desired. Separate means for disposal might be provided for the air leaving the hood 25 in order that the air blast might not interfere with the water flow issuing from the spray head 24 or otherwise interfere with any of the operations. From the standpoint of the vibrating screen to be used in connection with the hulling and cleaning method disclosed, a structure which 20 may be employed is available on the market under the trade name of Denver-Dillon Vibrating Screen manufactured by the Denver Equipment Company.

From the foregoing description it is evident 25 that various grains, such as wheat, rice, barley, oats, and rye may be hulled in their original dry condition, by the simple expedient of vibrating a grain column of suitable head with appropriate rubber balls 16 or similar balls, the column of balls and grain being rested upon a convenient, vibrated supporting surface such as the screen 10 or the plate 17. Also, the grain having 30 been hulled and having advanced from the bottom of the grain column 12, the hulls and other light materials are separated as by suction, and the hulled grain washed to eliminate 35 undesired foreign matter on the surfaces of the kernels and quickly dried before discharge from the apparatus.

With some grains it is sufficient to maintain 35 an adequate height of the grain column 12 without employment of the balls 16 or similar objects, and rely entirely upon the vibration and the pressure of the head of grain to effect the cracking or splitting of the grain hulls. For example, where the hulls of a particular grain require 40 a prior soaking or other heavy water treatment to accomplish adequate splitting, such will be effected.

Inasmuch as many variations of the generic 45 invention herein disclosed will become apparent to those skilled in the art, it is intended to cover all modifications which fall within the scope of the claims.

I claim as my invention:

1. A method for hulling grain comprising: establishing a column of unhulled grain upon a surface, the lower portion of said column containing a layer of contact objects larger than the grain and having surfaces capable of causing splitting and loosening of the grain hulls upon vibration of the grain with said objects; vibrating said column of grain and said objects to rupture and loosen the hulls of kernels of grain adjacent said objects; and removing from the column that portion of the grain whose hulls have been split and loosened.

2. A method as in claim 1 wherein the unhulled grain in said column is dry grain, and the contact objects have surfaces which are non-rup- 75 turable during the hulling treatment.

3. A method as in claim 1 including the step of simultaneously screening the grain during vibration of said column and following removal of the hulled grain from said column.

4. A method as in claim 1 including the additional step of separating the loosened hulls from the removed grain being hulled.

5. A method as in claim 1 wherein grain and hulls are continuously removed from the bottom of the column and unhulled grain is continuously added to the top of the column in quantity to maintain sufficient pressure upon grain in contact with said objects to cause said hulls to be cracked during vibration, the grain kernels remaining intact.

6. A method as in claim 1 wherein said surface is caused to move by said vibration and the removal of grain and hulls is effected from the bottom of said column under influence of said vibration as said surface moves.

7. A method as in claim 1 wherein said surface is caused to move by said vibration and the removal of grain and hulls is effected from the bottom of said column under influence of said vibration as said surface moves, said larger contact objects remaining in the column in contact with descending grain.

8. A method for hulling grain comprising: establishing a column of unhulled grain upon a surface capable of being vibrated to move the grain; providing in the lower portion of the column in contact with grain therein a plurality of objects capable of causing rupture of the hulls of the contacted grain upon vibration of said surface and column without rupturing the grain kernels; vibrating said surface and simultaneously supplying pressure on the grain to effect rupture of said grain hulls while avoiding rupture of the grain kernels; and causing ruptured hulls and their grain kernels to escape from the bottom of said column under influence of the vibration of said surface.

9. A method as in claim 8 wherein said objects are smooth surfaced and avoid damage of the grain kernels, and pressure is applied thereto and to grain being hulled by the weight of the column of grain and objects to cause splitting of the hulls of kernels in contact with said objects.

10. A method for hulling grain comprising: establishing a column of unhulled grain; supplying in a portion of said grain column a plurality of contact objects in contact with the grain, said objects having smooth surfaces which remain smooth during the treatment; vibrating the portion of said column containing said contact objects; and maintaining sufficient pressure on the grain contacted by said objects to cause the hulls of said grain to be cracked loose by such vibration and pressure while maintaining whole the individual kernels of grain themselves.

11. A method as in claim 10 wherein said pressure is accomplished by the head of grain constituting the column.

12. A method as in claim 10 wherein said contact objects are maintained in the lower portion of said column, and wherein cracked hulls and the respective grain kernels are removed from the bottom of the column.

13. A method as in claim 10 wherein said contact objects are maintained in the lower portion

of said column, and wherein cracked hulls and the respective grain kernels are removed from the bottom of the column, such removal being continuously accomplished and unhulled grain being continuously added to the upper portion of the column to maintain the column.

14. A method for hulling grain comprising: establishing upon a substantially flat supporting surface a column of dry grain to be hulled; commingling with the dry grain in the lower portion of said column a plurality of smooth surfaced objects which are larger than the grain kernels and remain whole during the treatment; vibrating said supporting surface while establishing a sufficient weight upon said lower portion to cause the dry hulls of the grain to split and become loosened under the vibrating action in the presence of said objects; and causing hulled grain and hulls therefrom to pass from the lower portion of said column.

15. A method as in claim 14 wherein said objects have rubber surfaces contacting said grain.

16. A method as in claim 14 wherein said hulls and hulled grain passing from said column are passed into a suction zone wherein said hulls are separated from the hulled grain by suction.

17. A method as in claim 14 including the additional step of separating the hulls from hulled grain.

18. A method as in claim 14 including the additional steps of separating the hulls from hulled grain, washing the hulled grain, drying the washed grain, and screening the grain during all of the steps.
